Primary Examiner — Caron D Veynar*Assistant Examiner* — Mehri Bajoul(74) *Attorney, Agent, or Firm* — Clark & Brody(57) **CLAIM**

The ornamental design for zippered pants, as shown and described.

DESCRIPTION

FIG. 1 is a front perspective view of a first embodiment of the zippered pants showing my new design;

FIG. 2 is a front side view thereof;

FIG. 3 is a rear side view thereof;

FIG. 4 is a left side thereof;

FIG. 5 is a right side thereof;

FIG. 6 is a top side view thereof; and

FIG. 7 is a bottom side view thereof

FIG. 8 is a front perspective view of a second embodiment of the zippered pants showing my new design;

FIG. 9 is a front side view thereof;

FIG. 10 is a rear side view thereof;

FIG. 11 is a left side thereof;

FIG. 12 is a right side thereof;

FIG. 13 is a top side view thereof; and,

FIG. 14 is a bottom side view thereof.

The parts of the pants shown in broken lines form no part of the claimed design.

1 Claim, 8 Drawing Sheets(56)
